ROY B. FEHR, OF CLEVELAND, OHIO.

RAIL JOINT AND INSERT THEREFOR.

Application filed June 6, 1923. Serial No. 643,733.

To all whom it may concern:

Be it known that I, ROY B. FEHR, a citizen of the United States, residing at Cleveland, in the county of Cuyahoga and State 5 of Ohio, have invented certain new and useful Improvements in Rail Joints and Inserts Therefor, of which the following is a specification, reference being had therein to the accompanying drawings.

10 This invention relates to railway track joints and is particularly concerned with a joint having a multipart insert between the meeting ends of the rails. The invention also relates to an insert for rail joints composed 15 of a plurality of pieces, some or all of which may be tapered or wedge shaped, which may be formed to seat on the top of the fish plates and which are preferably composed of metals of different degrees of 20 hardness, for example, some composed of low carbon or soft steel and others of high carbon or hard steel.

In the present practice of joining the ends 25 of electric railway rails together, by bringing them into more or less close contact and securing them in position by fish plates on opposite sides thereof, with each plate bridging the space between the rails and fastening to each rail, a space is left between 30 the rails which varies from a small minimum to a gap of considerable extent depending upon a number of factors including the care exercised in abutting the rails, the relative positioning, size and location of 35 the bolt holes in the fish plates and rails, the smoothness of finish on the rail ends, the angle between the end surfaces of the rails, and the varying atmospheric temperatures during the year.

40 It has been found that however minute the space between the rail ends may be, car wheels in passing along the rails tend to batter or peen over the ends of the rails into the space between the rails, thus forming 45 a slight depression in one or both of the rails which gradually increases and constitutes what is familiarly known as "cupping". It is also well recognized that cupping is one of the chief causes of failures 50 of seam-welded joints, which usually involve breaks through the fish plates or welded seams, since the cupped surface of the rail permits the rolling wheel to deliver a blow to the rail which must be largely 55 absorbed by the fish plates, and welded seams.

I have found that cupping of the rails may be largely, if not entirely, avoided by the use of a multipart insert assembled between the meeting ends of the rails at the 60 time the joint is being constructed. Furthermore, my improved form of insert possesses many other advantages including the formation of a substantially continuous metal surface between adjacent rails; the 65 substantially complete filling of the space between the heads of the rails with practically uniform pressure over the entire rail head which results in an effect approaching that of a continuous rail; good contact between the insert parts and the rail heads 70 without excessive compression of the rails; and retention of the insert parts in position by friction. It is equally as well adapted for use with new rails as with old rails.

75 These and other advantages will be more fully pointed out in the following specification, reference being had therein to the drawings attached to and accompanying the same, in which

Fig. 1 is a side elevation of a rail joint constructed in accordance with my invention.

Fig. 2 is an enlarged end elevation of the form of multipart insert shown in Fig. 1.

Fig. 3 is a side elevation of the insert shown in Fig. 2.

Fig. 4 is a sectional view taken on line 4-4 of Fig. 1 showing the relative position of the rail, fish plate and insert parts 90 when assembled.

Fig. 5 is a view similar to Fig. 4 but showing a form of insert for and assembled with a girder rail.

Fig. 6 shows a modified form of insert.

Referring to Fig. 1 two aligned, adjacent rails indicated by 1 are shown with a fish plate 2 spanning the gap between the ends of the rails and secured thereto. A similar fish plate (not shown) is similarly secured 100 to the opposite side of the rail as will be understood by those skilled in the art. 3 indicates, as an entirety, an insert composed of a central part 4 and side parts 5. The central part 4 is preferably shaped to conform to the outlines of the rail heads and is provided with converging, opposite side surfaces 6 which may have various degrees of slope or inclination. I prefer however to incline the surfaces 6 so that the total taper 105 of part 4 will lie between about one inch and one-half inch per foot which will give 110

angles lying between approximately 2.4° and 1.2° for each surface. Side parts 5 also preferably have an outline corresponding to the outline of the rail head and may have side surfaces variously inclined, but I prefer to incline surface 7, namely, that surface of each part which engages with the surface 6 of the central insert part 4, at a slight angle to the outer surface 8, which is the surface of each side part which engages with the head of the rail. The inclination of each surface 7 should preferably be about the same as that of each surface 6, namely, one-half inch to one-quarter inch per foot. The inclination of surface 8 is preferably that which conforms to the inclination of the rail end surface, which usually, but not always, is at right angles to the running surface of the rail. It is desirable though not essential that the insert parts be suitably shaped on their lower edges to conform to and seat upon the top surface 9 of the fish plate which thereby serves as a rest or supporting means for the insert parts during assembly as well as subsequent thereto. It is also desirable to have the three parts of the insert protrude about $\frac{1}{8}$ inch above the rail heads after these parts have been driven into place, so that the upper ends of the inserts can be peened over into irregularities in the upper ends of the rails previous to grinding.

I have found it advantageous to form side members 5 of comparatively soft material, for example, low carbon steel, and to form the central part 4 of harder material, for example, high carbon steel. When the insert is assembled and in use, the wide edge of the central part 4 will be exposed to and in contact with the wheels passing along the rails and will not be worn down more rapidly than the rails themselves. The soft material comprising the side parts 5 will be adapted to conform to the surface of the rail ends with which they contact and to engage with substantially the entire surface of the rail regardless of small variations of size or rough surface as well as to form close engagement over practically their entire surface with the central part 4.

The method of assembling my improved insert and constructing the joints is substantially as follows:

The fish plates having been secured by tightly pulled up bolts to the opposite sides of the rail ends, insert parts 5 of the proper thickness are placed in position and central part 4 inserted therebetween and driven into the position shown in Fig. 1. I prefer to utilize insert parts of such a size that the central part 4 may be inserted by hand approximately half way down between the side parts. Such an arrangement requires driving the central part into final position with sufficient force to insure the desired contact

between the outer parts 5 and the rail ends and to create enough friction between the parts to prevent displacement thereof under the usual condition of traffic along the rails. After the central part has been driven into final position the seams are welded, and the protruding top edges of the multi-part insert are peened over. Any rough surface projecting above the top of the rails may be ground or otherwise machined off to leave a smooth surface.

If the joint is to be arc welded the plates and rails are united by seam metal melted by an arc after the insert has been driven into place. Although the insert parts are so shaped as to be capable of remaining in position due to frictional engagement of the parts with each other and the rails, they may be additionally secured by welding across them and thus uniting them to the plates.

It will be apparent to those skilled in the art that I have provided an insert which may be readily and easily assembled in a rail joint, the parts of which will tend to remain in position without any additional securing means and which will substantially fill the space between the ends of the rails throughout the full vertical dimensions of the heads. Thus, regardless of the extent to which the rails will be worn down, the space between the rail ends will always be completely filled and the chief cause of cupping avoided. Furthermore, the inclination of the meeting surfaces of the insert parts is such that comparatively little force is required to assemble the parts and consequently the rails are placed under only moderate compression, which, in the case of seam welded joints, will not cause excessive stresses in the fish plates or welded seams. The initial pressure and friction however tend to remain the same throughout the life of the rails although the rail head may be worn down materially in use.

In Fig. 5 I have shown an insert 10 suited to a girder rail 11 which has a lip 12 projecting from one side thereof, the insert being like that shown in Figs. 1 to 4 inclusive except that it is shaped to cover the entire end surface of the head of the girder rail.

It will be obvious that my invention is applicable to rails of various sections other than T head or girder rails.

In Fig. 6 is shown a modified form of insert which comprises a part 13 having substantially parallel side surfaces 14 and a wedge shaped central part 15 and opposite side part 16 having respectively side surfaces 17 and 18 substantially parallel to surfaces 14 of part 13 and cooperating surfaces 19 inclined at an angle to surfaces 14, 17 and 18. Such an arrangement of parts is advantageous where the space be-

tween rail ends varies considerably since two wedge shaped parts of standard size may be employed with a third part of a suitable thickness which may be readily made from 5 standard plate stock with substantially parallel sides. Another advantage possessed by such insert construction is a slightly lower cost as compared with the insert shown in Fig. 2.

- 10 I have found that my improved insert is practically self sizing if the central part, as 4 or 15 is provided with substantially square lower edges or corners 20 as contrasted with rounded edges.
- 15 In repairing old track, particularly, where the space between rail ends varies, it simplifies installation of the insert if the parts are of a size to fit approximately the larger spaces. When a smaller space is 20 encountered and the central part 4 or 15 is being driven between the side parts, the lower corners or edges 20 will tend to shave or cut away enough metal from the side parts to provide an opening of sufficient size 25 to accommodate for the central part without creating excessive pressure on the rails. In this manner the insert more or less automatically adapts its size to the space it is to occupy.

30 Furthermore I have found that the use of sharp lower corners or edges on the central member is advantageous where the end surfaces of the rails diverge slightly downwardly and where it would ordinarily be 35 difficult to fit the insert closely at its lower end against the rails. By providing either or both side parts with extra thickness at the bottom or by inclining either or both of the side part surfaces which cooperate with 40 the central part at a greater angle than that of the central part I am able to ensure close fit of the insert parts over the entire rail head. After the side parts are assembled and when the central part is being driven 45 down it will shave off enough metal from one or both side parts to provide the desired close fit.

Having thus disclosed my invention as 50 illustrated in one practical form, what I desire to secure by Letters Patent is defined in what is claimed, it being recognized and understood that various changes may be made in the device shown by those skilled in the art without departing from the spirit 55 and the scope of my invention which is defined in what is claimed.

What is claimed is:

1. A rail joint comprising adjacent, 60 aligned rail ends spaced apart, means for securing the rail ends together, and a multipart insert completely filling the space between the heads of the rails.

2. A rail joint comprising aligned rail ends spaced apart, means for securing the 65 rail ends together, and a multipart insert

completely filling the space between the heads of the rails, certain of the insert parts having inclined meeting faces.

3. A rail joint comprising aligned rail ends spaced apart, means for securing the 70 rail ends together, and an insert composed of a plurality of wedge shaped parts substantially filling the space between the heads of the rails.

4. A rail joint comprising aligned rail 75 ends spaced apart, fish plates on opposite sides of the rails, seam weld metal joining the plates to the rails, and a multipart insert between the rail ends and joined to the plates by seam weld metal.

5. A rail joint comprising aligned rail ends spaced apart, fish plates on opposite sides of the rails and secured to each rail end, and an insert composed of a plurality 80 of wedge shaped parts adapted to be assembled between the rail ends in a manner to exert compressive force on the said rails.

6. A rail joint comprising aligned rail ends spaced apart, fish plates on opposite sides of the rails, seam weld metal joining 85 the plates to the rails, and a multipart insert substantially filling the space between the heads of the rails.

7. An insert for a rail joint comprising 90 three parts having inclined meeting surfaces.

8. A multipart insert for a rail joint comprising a central wedge shaped part, and two side wedge shaped parts each composed 95 of material softer than the material in the said central part.

9. A multipart insert for a rail joint comprising a central part composed of hard steel and two side parts composed of steel relatively soft as compared with the said central part.

10. A multipart insert for a rail joint conforming in shape substantially to the cross sectional outline of a rail head and adapted to seat on the fish plates when in assembled position in a rail joint, the said insert comprising a central downwardly tapered wedge shaped part and two upwardly tapered wedge shaped parts arranged on either side of the said central part.

11. An insert for a rail joint comprising a central part and two side parts, the side parts having engaging wedge surfaces inclined at angles of from about 1.2° to 2.4° and the said central part having wedge surfaces engaging with the wedge surfaces of the said side parts and inclined in conformity to the said surfaces of the side parts.

12. A multipart insert for a rail joint conforming in shape substantially to the cross sectional outline of a rail head and adapted to seat on the fish plates when in assembled position when in the rail joint, the said insert being slightly larger than the rail head, whereby when the insert is assembled in the 125

rail joint it will project slightly above the top of the rail heads.

13. A multipart insert for a rail joint comprising a tapered central member having substantially square lower edges, and two side parts each composed of metal relatively soft as compared with the metal of the said

central part, one of the said side parts being tapered to correspond with the adjacent surface of the said central part.

In witness whereof, I hereunto affix my signature this 11 day of May, 1923.

ROY B. FEHR.
